US0D1022258S

(12) **United States Design Patent** (10) Patent No.: **US D1,022,258 S**
(45) Date of Patent: ** Apr. 9, 2024

(54) **VENTED FINISH BEAD**

- (71) Applicant: **Alabama Metal Industries Corporation**, Birmingham, AL (US)
- (72) Inventors: **Gary George Baltz, Jr.**, Mountain Brook, AL (US); **Frederic C. Mayer, Jr.**, Hoover, AL (US)
- (73) Assignee: **Alabama Metal Industries Corporation**, Birmingham, AL (US)
- (**) Term: **15 Years**
- (21) Appl. No.: **29/790,947**
- (22) Filed: **Dec. 22, 2021**

Related U.S. Application Data

- (63) Continuation of application No. 29/699,048, filed on Jul. 23, 2019, now Pat. No. 940,350, which is a continuation of application No. 16/509,181, filed on Jul. 11, 2019, now Pat. No. 10,731,335.

CLAIM

The ornamental design for a vented finish bead, as shown and described.

DESCRIPTION

FIG. 1 is a top elevation view of a vented finish bead showing our new design;

FIG. 2 is a front view of the vented finish bead;

FIG. 3 is a back view of the vented finish bead;

FIG. 4 is a left side view of the vented finish bead;

FIG. 5 is a right side view of the vented finish bead;

FIG. 6 is a top side view of the vented finish bead;

FIG. 7 is a bottom side view of the vented finish bead; and,

FIG. 8 is a bottom elevation view of the vented finish bead. The broken lines in FIGS. 1-8 represent portions of the vented finish bead and form no part of the claimed design.
